MEANS FOR TREATING CLUBFOOT
Philip R. Brachman, 25 E. Washington St.,
Chicago 2, Ill.

Filed May 19, 1961, Ser. No. 111,263
5 Claims. (Cl. 128—80)

This invention relates generally to corrective apparatus for the treatment of talipes or clubfoot and more particularly relates to improved apparatus of the type disclosed in U.S. Patent No. 2,482,646, and of which I was one of the co-inventors.

Talipes, the deformity commonly known as clubfoot, can assume a variety of forms such as, for example, talipes varus wherein the afflicted foot is bent inward, or talipes valgus wherein the foot is bent abnormally outward. As described in the aforementioned patent, previous treatment of such deformed feet, particularly among children, generally involved some preliminary corrective manipulation after which an uncomfortable and somewhat immobilizing cast or splint was applied. The purpose of the cast or splint was to retain the afflicted foot in the improved position and prevent the same from returning back to the original deformed position. The many disadvantages inherent in the described prior method of treatment were of course apparent, and there thus existed a great need for a new and better method of treating such afflictions.

The apparatus of the aforementioned patent most admirably filled the described need by affording a new and most efficient method for the treatment of clubfoot. In general, that apparatus comprised a pair of shoes having means for interconnecting the same in fixed spaced apart relationship and pivotal means which prevented the foot from moving beyond the improved position toward the original deformed position while at the same time permitting movement of the foot within substantially the normal range of movement in a direction from the improved position opposite that of the deformed position. Thus correction was applied while at the same time permitting therapeutic exercise and a certain degree of walking freedom.

Although the patented apparatus unquestionably represented a most significant advancement of the art, it has been found, through continued experimentation and use thereof, that the same contained certain disadvantageous features. It may be remembered that in the patented apparatus the attachment for each shoe included a pair of metal plates having the same configuration as the shoe sole and a pair of spacer blocks positioned therebetween. A pair of metal bars were employed to pivotally and adjustably interconnect the two shoes. Numerous threaded positioning holes were drilled in the metal plates to provide individual adjustment means for each end of each of the interconnecting bars. The patented apparatus thus comprised a relatively complicated device in which the necessary adjustments were numerous and sometimes difficult to make. Attachment of the apparatus to the shoes was a time consuming task necessitating the use of a substantial number of screws, bolts, or the like. In addition, the apparatus was unduly cumbersome, excessive in weight and expensive to manufacture.

It is therefore an important object of this invention to provide improved apparatus of the character described which overcomes all of the aforementioned disadvantages while at the same time retaining all of the beneficial results of the patented apparatus.

Another object is to afford improved apparatus of the character described which is extremely light in weight. In this regard, the invention employs only one interconnecting bar and eliminates entirely the metal plates of the patented apparatus.

2

A further object is to provide improved apparatus of the character described having simple-to-operate means for readily adjusting the prescription angle, i.e., the angles defined by the longitudinal axes or center lines of the feet of a user in a prescribed improved position and from which neither foot alone is movable toward its deformed position. Thus, the apparatus may be readily progressively adjusted as the correction of the deformity is increased. A related object is to provide such apparatus wherein the prescription angle is readily variable to adapt the apparatus for treatment of talipes of the type wherein the forward ends of the feet are turned outwardly relative to each other (valgus), and of the type wherein they are turned inwardly toward converging relationship (varus).

Still another object is to afford improved apparatus of the character described which may be simply and quickly attached to the shoes and in which many of the parts heretofore required for this task have been eliminated.

Still a further object is to provide improved apparatus of the character described which, while preventing movement of a deformed foot between the improved position and the deformed position, permits exercising the foot and leg by movements thereof outside the range between the deformed and improved positions.

Yet another object is to afford improved apparatus of the character described which enables an afflicted user to move the feet to and fro relative to each other in a manner simulating walking.

Yet a further object is to provide improved apparatus of the character described which may be inexpensively fabricated and yet is most efficient for the purposes intended.

With the foregoing and other objects in view which will appear as the description proceeds, the invention consists of certain novel features of construction, arrangement and a combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawing:

FIG. 1 is front elevational view of apparatus for the treatment of talipes embodying the principles of the invention;

FIG. 2 is a bottom plan view with portions broken away of otherwise removed to facilitate illustration and showing prescription angle for the type of deformity 60 wherein the heel-to-toe-axes or center lines of the deformed feet converge, and showing also, in dotted outline, the relative displacement of one of the shoes about an axis at the other shoe;

FIG. 3 is a similar view with portions removed and showing the shoes in a position within the normal range of their independent pivotal motion away from the deformed position;

FIG. 4 is an enlarged and inverted sectional view taken on the plane of line 4—4 in FIG. 3 and viewed in the direction indicated;

FIG. 5 is a sectional view taken on the plane of line

5—5 in FIG. 4 and viewed in the direction indicated; and

6 FIG. 6 is a sectional view taken on the plane of line 6—6 in FIG. 4 and viewed in the direction indicated.

Referring now to FIG. 1 of the drawings, a novel improved apparatus embodying the principles of the invention is indicated generally by the reference character 10. The apparatus 10 comprises a pair of shoes 12 and 14 of ordinary construction, each of said shoes having a sole 16, a heel 18 and a lace 20 or other suitable means for holding the shoe on the foot of a wearer thereof.

The shoes 12 and 14 are pivotally connected together by novel connecting means which are indicated generally by the numeral 22. The connecting means 22 comprises a pair of identical heel assemblies 24, each of which is connected to the heel 18 of a shoe 12 or 14. Turning to FIG. 4 of the drawings, it will be seen that the heel assembly 24 comprises an indexing plate 26 having a plurality of indexing holes 28 formed therein and positioned in radially spaced relationship as indicated in FIG. 5. Connected to the indexing plate 26 is an internally threaded central hub 30. The hub 30 terminates in a reduced diameter portion 32 thereby affording a shoulder 34. The indexing plate is preferably integrally made from a rigid metal or the like, and the same may be mounted on the heel 18 by any suitable means such as the screws 36.

Cooperating with the indexing plate 26 is a centrally apertured locking plate 38. Integrally formed, or otherwise connected to the locking plate 38 is an outwardly projecting locking pin 40, said locking pin being adapted to fit into any of the indexing holes 28. It will thus be noted that when the locking plate 38 is positioned on the hub 30 the same rests on the shoulder 34 thereof with the locking pin 40 being received in one of the indexing holes 28. A locking screw 42 is threadedly received within the hub 30 for locking the two plates 26 and 38 in any desired positioning relationship for purposes which will subsequently be more fully described. A suitable washer such as 44 may likewise be employed for facilitating the unscrewing of the locking screw 42 when desired.

Connecting the two heel assemblies 24 is a rigid connecting bar 46. The connecting bar 46 is provided with an opening adjacent each end thereof of sufficient dimension to freely accommodate the hub 30 therethrough. When operationally assembled, the connecting bar 46 is positioned between the plates 26 and 38 at each end thereof as indicated in FIG. 4. It is important to note, however, that the shoulder 34 of the hub 30 prevents the locking plate 38 from impinging upon the end of the connecting bar 46 so that the latter is thus free to rotate about each of the hubs 30.

A protective disc 48 of neolite, leather, or the like, is glued or otherwise suitably connected to the locking plate 38 for purposes of shielding the head of the locking screw 42. The protective disc 48 is provided with a central aperture 50 so that free access may be had to the screw 42 which is countersunk in said aperture. When required for purposes of better balance, a toe piece such as 52 may be glued or otherwise suitably connected to the sole 16 of the shoe as indicated in FIGS. 1, 2 and 3. The toe piece 52 may likewise be made of neolite, leather, or the like.

The operation of the apparatus 10 may now be described with particular reference being had to FIGS. 2 and 3 of the drawings wherein it will be noted that the apparatus has been adjustably set to provide a desired prescription angle for the treatment of an in-toeing or talipes varus condition. It will thus be noted that the locking pin 40 is positioned anteriorly of the connecting bar 46 so that any further motion of the shoes 12 and 14 toward each other is thereby effectively prevented. In other words, the position shown in FIG. 2 is the improved prescription position beyond which the shoes can-

not be moved back toward the original deformed position. However, as seen in FIG. 3, the shoes are nonetheless free to rotate within any normal range of movement in a direction opposite from the deformed position. Similarly, the free rotatability of the connecting bar 46 about either of the hubs 30 permits the patient to move either leg forwardly or rearwardly in a walking motion as indicated by the dotted line showing.

For purposes of treating an out-toeing or talipes valgus deformity, it is simply necessary to adjust the relative position of the locking pin 40 so that the same is positioned posteriorly of the connecting bar 46. Such adjustment may be readily accomplished by loosening the locking screw 42. The locking plate 38 may then be raised sufficiently to permit rotation of the same until the locking pin 40 is positioned in the proper indexing hole 28 to afford the desired prescription angle. The operation of the apparatus in treating an out-toeing condition is of course the same except that in this case, outward movement of the feet is limited by the locking pin 40 whereas inward movement of the feet toward each other is unlimited.

In order to provide the greatest degree of adjustability of the prescription angle, the indexing plate 26 should be formed with as many radially spaced indexing holes 28 as is practicable. Thus, in the embodiment illustrated, there are 20 such indexing holes in each of the indexing plates. It will thus be appreciated that the positioning of the locking pin 40 in each adjacent indexing hole 28 provides a change in the prescription angle of approximately 18°.

From the foregoing description and drawings, it should be apparent without further description that I have provided a novel and most efficient improved apparatus for treating clubfoot. The apparatus is light in weight and may be quickly and simply adjusted to treat both types of talipes or to vary the prescription angle as desired. In this regard, while the connecting bar 46 is preferably made of a rigid metal, the same may nonetheless be bent slightly to effect inversion or eversion, if desired. In addition, the connecting means of the apparatus may be inexpensively manufactured, has a greatly reduced number of parts, and is readily attachable to a pair of shoes.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. In apparatus of the class described, a pair of shoes, a pivot point depending from the heel of each of said shoes, means pivotally connected to said pivot points, said means spacing said shoes apart and means under the heels of said shoes for adjustably limiting the pivotal movement of each of said shoes in one direction and permitting the pivotal movement of said shoes in the opposite direction, said first mentioned means comprising a rigid spacing bar having an opening at either end thereof for accommodating said pivot points therethrough, said last mentioned means comprising a heel assembly secured to the heel of each of said shoes, said heel assembly comprising a pivot point, locking means cooperative with said spacing bar for limiting said pivotal movement and indexing means for varying the relative position of said locking means, said indexing means comprising an indexing plate secured to said shoe heel, said indexing plate being formed with a plurality of indexing holes spaced radially around the circumference thereof, and a central hub depending from said indexing plate to afford said pivot point, said locking means comprising a locking plate rotatably mounted on the free end of said hub, said spacing

bar positioned between said locking plate and said indexing plate, and a locking pin projecting upwardly from said locking plate and positionable in any of said indexing holes for limiting the pivotal movement of said spacing bar about said hub.

2. In apparatus of the class described, the combination with a pair of shoes, of a heel assembly secured to the bottom of the heel of each of said shoes, said heel assembly comprising pivot means, locking means and indexing means for adjustably positioning said locking means, and a rigid spacing bar pivotally connected at each end thereof to said pivot means, said locking means cooperating with said spacing bar for limiting the pivotal movement in one direction only of each of said shoes about said pivot means, said heel assembly comprising an indexing plate secured to said heel and a central hub depending from said indexing plate to afford said pivot means, said spacing bar having an opening at each end thereof whereby the same is pivotally mounted over said hub, said indexing means comprising a plurality of indexing holes formed in said indexing plate, said indexing holes being radially spaced to provide a circle having said hub as the center thereof, in which said locking means comprising a locking plate rotatably mounted on the free end of said hub, said spacing bar being positioned between said indexing plate and locking plate, and a locking pin projecting upwardly from said locking plate, said locking pin being positionable in any of said indexing holes and cooperating with said spacing bar to limit said pivotal movement of said shoes.

3. The apparatus of claim 2 in which a toe piece is secured to the sole of each of said shoes.

4. Apparatus for the treatment of clubfoot comprising a pair of shoes, a circular indexing plate secured to the

5 heel of each of said shoes, said circular plate being formed with a plurality of radially spaced indexing holes, a central internally threaded hub integrally formed with and depending from said indexing plate, said hub including a reduced diameter portion affording an annular shoulder, an elongated rigid spacing bar having an opening adjacent each end thereof pivotally connected to said hubs, a centrally apertured cooperating locking plate rotatably mounted on said reduced diameter portion so that the same rests on said annular shoulder, said spacing bar being retained between said indexing plate and said locking plate a locking pin integrally formed with and projecting upwardly from said locking plate, said locking pin being positionable in any of said indexing holes, and a locking screw threadedly received in said hub for locking said locking plate in any selected relative position with said locking pin positioned in any selected one of said indexing holes.

10 5. The apparatus of claim 4 in which a centrally apertured circular protective disc is secured to the outer surface of said locking plate.
